UNITED STATES PATENT OFFICE.

JAMES A. CAREY, OF PITTSBURGH, PENNSYLVANIA.

SUPPORT FOR CONTAINERS.

Application filed October 28, 1921. Serial No. 511,015.

This invention relates to an improvement in carboy supports and inclinators of the type shown in my Letters Patent No. 1,400,025, of December 13, 1921.

5 The present invention has for its object to provide certain improvements over the construction shown in my said patent by which the device is simplified and by which the carboys can be more quickly and easily placed 10 therein and manipulated.

My invention may be readily understood by reference to the accompanying drawings in which:

Fig. 1 is a perspective view of a device constructed in accordance with my invention, 15 showing a carboy therein;

Fig. 2 is a vertical section through the device and a carboy casing, the carboy being shown in elevation;

20 Fig. 3 is a side elevation showing one of the end members adapted to be clamped against the carboy casing for pivotally supporting it;

Fig. 4 is a detail view of one of the telescoping side rods that connect the end members shown in Fig. 3;

Fig. 5 is a detail view of a locking means for normally holding the carboy against inclination;

30 Fig. 6 shows a modification of the locking means shown in Fig. 5.

In the drawings, A designates a standard carboy surrounded by the usual casing or crate B on which are side strips C.

35 My invention comprises a pair of end members 5 having a horizontal top part 6, from each of which projects a trunnion 7. Depending from the horizontal bars 6 are central vertical parts 8, and 9 are inclined bracing members. The end members thus have a truss shape so that they have a maximum 40 strength. Each of the end frames 5 preferably comprises a single casting which may be of malleable iron, or cast iron with which

45 a certain grade of steel has been mixed or poured, so that they are strong and rigid and not liable to crack or break. The ends of the cross bar 6 are provided with horizontally extending slots 10.

50 The two end members or plates 5 are connected at the sides by rods passing through the slots 10. The rods are preferably made of two sections 11 and 12, having a threaded telescoping connection. Section 11 is preferably non-circular in cross section, and has a head 11' on the outer end thereof. As shown,

it is hexagonal in cross section. The inner end is provided with a longitudinally extending threaded bore or hole.

Section 12 is provided with a hexagonal 60 or other shaped head portion through which passes a pin 12' which serves as a handle for turning the rod. At 12^a the rod is reduced and 12^b is a threaded extension adapted to fit into the threaded bore in section 11. The 65 head of section 12 is slightly larger than section 11 in cross section. This prevents the rod from passing through the slot to such an extent that the pin 12' would contact with the bar 6.

70 The end clamping members 5 are designed to be pivotally supported on the trunnions 7 in supporting frame members 15 having bearings 16 therein in which the trunnions are adapted to be set. The supporting frame 75 members 15 may be adjustably connected relatively to each other by tie bolts or rods 17. Adjustment is effected by proper positioning of the nuts on the tie bolts, as explained in my aforesaid application. The tops of the 80 frames 15 may be held in proper spaced relation by a shoulder on the trunnions 7 which bears against the ends of the bearings 16, as shown in Fig. 2. Other supporting frames, however, than the one shown might readily 85 be substituted.

In use, the members 5 are connected by the adjustable side rods which pass through the slots 10. They are then passed over the crate B until the top portions 6 are below 90 the side strips C. The side rods and the members 5 are then shifted sideways until the rods are substantially equidistant from the center of the trunnions but close against the sides of the crate, so that the crate is 95 properly centered. The slots 10 will serve to assist in gauging when the carboy is centered, as the eye can readily measure the positions of the rods in the slots to locate them in corresponding positions. Then the rod 100 sections 12 are turned by means of pins 12' to screw their respective threaded extensions 12^b into the threaded bores in the respective sections 11. The section 11 being hexagonal, or non-circular, does not turn in the 105 slot 10, so that the two sections of each rod may be easily screwed together.

Screwing the rod sections together draws the end clamping members 5 into contact with the crate, and the rod sections 12 are turned 110 until the crate is tightly clamped between the members 5. The carboy can then be easily

lifted and carried, the trunnions 7 serving as handles. When transported to the supporting stand, the trunnions may be set into bearing 16 in the end supporting frame members 15. The trunnions are of sufficient length to enable them to be grasped after they have been set in the bearings, so that liability of injury to the fingers is avoided. After the carboy has been pivotally supported in this manner in the supporting frame, it can be tilted to any angle to remove all of the contents.

The advantage of having the rods which connect the clamping members telescope is that the clamping members can be adjusted to engage crates of different sizes and yet the ends of the rods will always project the same distance beyond the clamping members. Therefore, the ends of the rods will never come into contact with the supporting frame members, as would be the case if the rods could not be shortened or lengthened. This is especially advantageous where there is only a slight difference in the size of the carboys or crates, as it is not then necessary to effect a change in the length of the supporting frame. By having the side rods adjustable laterally in the slots 10, the device can be more easily applied to the crates and enables it to be more conveniently adjusted for carboys of different sizes.

For normally holding the carboys against tilting or for preventing the accidental inclination, I preferably employ a suitable locking means, the preferred form of which is shown in Fig. 5. Cast at one side of the bearing 16 of one of the end frame members is an enlargement 20 having a chamber 21 therein in which is a spring for yieldably urging a slideable latch or plug 22 outwardly. A knob 23 is connected by a pin 24 to the plug by means of which the plug may be retracted, manually. In the trunnion 7 is a recess, preferably in the form of a longitudinally extending groove. The end of the plug normally projects into the groove to hold the trunnion against rotation. When it is desired to tilt the carboy, the knob 23 is pulled to retract the end of the plug from the groove. When the carboy swings back to normal position, the spring will act to again force the plug into the groove when it comes into register therewith. The provision of a groove enables the trunnion to move longitudinally according to variations in the sizes of carboys, without necessitating a change in the length of the frame, and the parts need not be so accurately adjusted.

As a modification of the locking means shown in Fig. 5, the arrangement shown in Fig. 6 may be employed. In the construc-

tion, a hole is drilled through one of the trunnions 7 and a groove is formed in the bearing 16. A removable pin 25 is passed through the trunnion and the lower end thereof extends into the groove to hold it against rotation. To tilt the carboy the pin must be removed.

The depending parts of the end members 5 project down along the sides of the crate to hold it firmly and rigidly and present a large surface to engage the crate, to hold it against movement. This surface is amply sufficient to keep the crate from slipping in any direction in which it is tilted. Being in the form of a truss, the end clamping members have a maximum strength.

I claim as my invention:

1. A support for containers comprising a pair of end members adapted to be clamped to two sides of a container, said members having laterally extending slots therein, means for connecting and clamping said members to a container comprising rods, said rods being formed of sections connected together for adjustment as to overall length, one section of which is non-rotatably mounted in a slot of one of the members and the other section rotatably mounted in a slot of the other member, each section having a head outwardly of said slots providing shoulders to abut the end members exteriorly, the heads of the rotatable sections affording means for engagement to effect turning, and means for pivotally supporting the end members. 95

2. A support for containers comprising a pair of end members adapted to be clamped against two sides of a container, said members having laterally extending slots therein, trunnions on said end members, an adjustable supporting means having bearings therein for engaging the trunnions, and means for connecting said end members and holding them in clamped relation with a container comprising a pair of rods, one of which is adapted to extend along each of the other two sides of the container and to pass through the slots in the end members, each of said rods being comprised of two sections, one of which is non-circular in cross section whereby it is held from rotating in the slot and the other being adapted to rotate in the slot, each section of said rod having a head outwardly of said slots providing shoulders to abut the end members exteriorly, the heads of the rotatable sections affording means for engagement to effect turning, and a threaded connection adapted to vary the overall length of the rod when the one section is turned relatively to the other. 110

In testimony whereof I affix my signature.
JAMES A. CAREY.
